VAPOR VACUUM PUMP OF THE DOUBLE
JET TYPEPaul Alexander, Berkhamsted, and Cecil Whiley,
London, EnglandApplication May 26, 1945, Serial No. 596,035
In Great Britain April 21, 1945

1 Claim. (Cl. 230—101)

1

This invention relates to vapor vacuum pumps of the double jet type.

Mercury is the liquid usually vaporized in vapor pumps but other liquids, such as oils, are employed. In pumps of this type mercury vapor from a mercury boiler ascends a central tube, the upper jet being fixed at the top of the tube, while the lower jet is fixed about halfway up the tube; both jets are supplied with vapor from the central tube, and the vapor issues from the jets into the annular space between the central tube and the outer tube constituting the body of the pump. The efficiency of the pump for a given vacuum depends largely on the density of the vapor issuing from the two jets and on the downward velocity of the molecules in this vapor.

Now it has been found that, in the described arrangement in which the two jets are supplied with vapor from the same source, it is generally impracticable to design the two jets so as to produce vapor jets with the desired density and velocity. There is necessarily a fall in vapor pressure from the bottom to the top of the central tube to produce a flow up the tube, and the pressure at one of the jets depends on the rate of flow through the other jet. The two jets therefore are interdependent.

According to the invention, the two jets are supplied with vapor through two non-communicating passages from two non-communicating evaporating surfaces of two communicating masses of liquid. The upper jet may be supplied with vapor through a central tube descending below the level of the liquid in the boiler and separating the liquid in the boiler into a central portion within the tube and an annular portion outside the tube, and by the lower jet being supplied with vapor from the annular portion of the liquid through a tube between the central tube and the pumping space, and holes in the central tube below the level of the liquid giving communication between the two portions. The tube through which vapor is supplied to the lower jet may be connected with the outer wall of the pumping space through a liquid seal, through which liquid condensed in the pumping space returns to the annular portion of the liquid in the boiler.

In the accompanying drawing, which shows in a single figure by way of example a form of pump embodying the invention in vertical section, a mercury boiler 1, containing mercury normally up to the level of the dotted line 2, with heater 3, supports the central vapor tube 4 and the outer tube 5 forming the body of the pump, which

2

terminates above in the inlet 6 of the pump. The upper annular jet 7, with annular orifice 8 is fixed on the top of the central tube 4. The vapor from the mercury in the boiler, passing up the tube 4 enters the jet 7 through holes 10 in the central body of the jet and issues from the orifice 8 into the pumping space 11 between the tubes 4 and 5.

The lower jet has its outer member 12 fixed 10 to the tube 4, while its inner member 13 is fixed to the top of a tube 14 attached to the outer tube 5 at 15.

The mercury in the boiler is separated into 15 two portions, a central portion inside the tube 4 and an annular portion between the tubes 4 and 5. The two portions are in communication through the holes 19 in the tube 4 below the mercury level 2, and the two portions are heated together by an electric heater in the space 3.

20 Mercury evaporated from the annular portion ascends into the space 16 between the tubes 4 and 14 and issues from the lower jets 12, 13. The evaporation from this portion is independent 25 of that from the central portion, and the vapor pressure in the tube 4 leading to the upper jet may differ from that in the space 16 leading to the lower jet, any difference in vapor pressure being compensated by a difference of level of the mercury inside and outside the tube 4.

30 The upper jet, therefore, operates independently of the lower jet, and the quantity of vapor issuing from each jet depends only on the dimensions of the jet and the temperature at which the mercury is maintained.

35 The outer tube 5 is surrounded as is customary by a water jacket 20, and the outlet 21 of the pump leads from the bottom of the space 11 to the backing pump. The mercury vapor from the two jets is condensed by the cooled wall 5 and falls into the space 22 between the tubes 40 14 and 5. A mercury seal is formed at this point by the channel 23, and the condensed mercury passes through holes 24 in the tube 14 and, overflowing the channel 23, returns to the boiler.

45 As shown in the drawing, the outer tube 5 preferably has parallel walls at its upper part surrounding the jet 7, the annular space between the tube 5 and jet 7 of width A determining in large measure the rate of evacuation of the pump.

50 As described and claimed in co-pending application No. 596,034 the tube 5 diminishes in diameter by the inclusion of a conical wall just below the jet 7, which conical wall joins up with the parallel walls of the lower part of the tube 55 5, so that the tube 5 diminishes in diameter at

a point near jet orifice level so that the length of vapor jet measured along a line B with angle 15 degrees from the general pumping direction, indicated by the line C, does not exceed 2.6 times the width A of the annular space at jet orifice level.

Further as described and claimed in co-pending application No. 596,036 a water jacket 25 may surround, but not touch, the tube 4, for a length just below the jet orifice 8 downwards, the jacket having inlet and outlet pipes 26 by which it is continuously supplied with cold water.

As fully explained in the aforesaid co-pending application No. 596,036, the efficiency of the pump is further increased by the employment of this inner jacket since vapor molecules are thereby prevented from striking the hot tube 4 and achieving a random velocity which enables such molecules to collide with molecules issuing from the jet 8 and diminish the downward component 20 of their velocity.

We claim:

A vapor vacuum pump comprising a boiler for the vapor, a central tube depending into said boiler and having apertures in its depending part, an outer tube forming with said central tube an annular space in said boiler, an intermediate tube between said central and outer tubes forming inner and outer annular spaces respectively therebetween, upper and lower annular jets supplied with vapor from the boiler respectively through the central tube and the inner annular space, and a liquid seal between the lower end of said intermediate tube and said outer tube into which seal falls condensed vapor from said jets and from which the condensed vapor returns to said annular boiler space.
